Primary Examiner — John Windmuller*Assistant Examiner* — Steven Czyz*(74) Attorney, Agent, or Firm* — Dennemeyer & Associates, LLC(57) **CLAIM**

The ornamental design for a pipeline pig, as shown and described.

DESCRIPTION

FIG. 1 is a perspective view of the pipeline pig;
FIG. 2 is a front elevational view of the pipeline pig, the rear, right and left side elevational views being identical thereto;
FIG. 3 is a top plan view of the pipeline pig, the bottom plan view being a mirror image thereof;

FIG. 4 is a perspective view of a second embodiment of the pipeline pig;

FIG. 5 is a front elevational view of the second embodiment of the pipeline pig, the rear, right and left side elevational views being identical thereto; and,

FIG. 6 is a top plan view of the second embodiment of the pipeline pig, the bottom plan view being a mirror image thereof.
